ABSTRACT OF THE DISCLOSURE

A method for producing a multiple-color soap bar by directing high energy electrons toward a surface of a soap bar, interpositioning, between the bar surface and the electron source, a shield having a design therein, and causing the design configuration to be applied to the soap bar by coloration or a change in color of the portion of the bar exposed to the electron radiation; and the modification of such method wherein the bar of soap to be irradiated contains a high energy electron color-sensitive dye; and the further modification of such method wherein the design is tapered through the shield to allow substantially all radiation passing into the design to emerge therethrough without striking the radiation impenetrable material of the shield.

BACKGROUND OF THE INVENTION

This invention relates to a process for producing a multiple colored bar of soap or other like material. More particularly it relates to utilizing high energy electrons to produce a color change in a dye-containing colored bar of soap.

Dyes known to be sensitive to radiation have generally been used to indicate the presence of sterilizing atomic radiation, viz they have been used in water solutions or in printing inks absorbed upon materials for use as radiation dosimeters. Radiation-sensitive dyes have also been used for imprinting symbols upon light-sensitive data recording materials (U.S. Pat. No. 2,953,454).

For many years the soap industry and others have been interested in permanently identifying soap bars—that is, they have been interested in being able to link a bar of soap by means of an indicia to its brand or source after the consumer has purchased the bar and put it into usage. The present practice is to cut an indicia upon the surface of the bar penetrating only a fraction of an inch into the bar. Once this bar has been put into use, the outer soap is worn off the bar and the indicia is obliterated.

Many techniques have been explored in the effort to permanently identify a soap bar. One known technique involves forming an aperture in a soap bar and introducing a distinctive soap insert into the aperture (U.S. Pat. No. 2,423,435). This technique and other methods for mechanically meshing two separate different-colored soaps have not proved entirely satisfactory due to difficulties in merging the two soaps into a completed bar, keeping the inserted soap from coming out of the bar and the commercial impracticality of purchasing or making costly and complex additional machinery.

SUMMARY OF THE INVENTION

We have discovered that high energy electron radiation will induce a change in color or a fading or bleaching in color of commercially available colored soap bars. Further, we have discovered that incorporating certain dyes into the soap bar to be irradiated will effectuate a deeper color contrast between the irradiated and the non-irradiated portions of soap, which color contrast will be

2

maintained in the bar for a long period of time. In addition, we have discovered that a more sharply defined color or contrast may be produced in the soap bar through the use of a radiation shield having a tapered design cut-out.

Therefore, it is an object of this invention to temporarily identify a bar of soap for purposes of determining retail sales turnover, tagging a production run, and the like.

It is also an object of this invention to provide a process for permanently identifying a bar of soap.

It is another object of this invention to provide a process for producing a soap bar having a distinctive indicia.

Another object of this invention is to provide a process for producing, in a few simple additional steps, a bar of soap having a distinctive indicia imprinted in depth therein so as to be visible throughout long usage of the soap bar.

Still another object of this invention is to provide a process for producing an indicia bar of soap containing an electron radiation-sensitive dye and having a sharply defined indicia which will be clearly visible throughout the useful life of the soap bar.

A further object of this invention is to provide novel soap bars having a distinctive indicia produced by exposure to high energy electron radiation, which indicia is permeated throughout the bar so as to be visible even after portions of the bar have been worn away through washings with this bar.

Other objects and advantages and a further understanding of the present invention will become more apparent from the ensuing description and examples, taken in conjunction with the accompanying drawings in which:

BRIEF DESCRIPTION OF THE DRAWINGS

FIG. 1 represents a schematic view of a batchwise, tray-by-tray process for irradiating soap bars with high energy electrons.

FIG. 2 is a perspective view of the indicia bar.

FIG. 3 is a cross sectional view of the indicia bar of FIG. 2 taken along line 3—3.

FIG. 4 is a top view showing one type of radiation shield which can be used in the irradiation process illustrated in FIG. 1.

FIG. 4A is a partial cross-section taken along line 4A—4A of FIG. 4.

FIG. 5 is a top view showing another type of radiation shield which can be used in the tray-by-tray irradiation process illustrated in FIG. 1.

FIG. 5A is a partial cross-section taken along line 5A—5A of FIG. 5.

FIG. 6 is a partial cross-section of one type of radiation shield.

FIG. 7 is a partial cross-section of a radiation shield having tapered apertures.

FIGS. 8, 9, 10 and 11 are structural formulas for certain dyes useful in the practice of this invention.

FIG. 12 illustrates graphically the depth imprinting profile curves for single and double bombardment of a $\frac{3}{4}$ -inch thick soap bar.

FIG. 13 is a graphic illustration of the depth of penetration curves for high energy electron beams of varying energies.

DESCRIPTION OF THE PREFERRED EMBODIMENTS

In a specific embodiment, our invention may be exemplified by incorporating an effective amount of a herein-after described radiation-sensitive dye or dye mixture which undergoes permanent color change upon irradiation into a bar of soap or other like material; directing high energy electron radiation toward a surface of the bar; in-

terpositioning between that surface of the bar and the source of the radiation a radiation shield having a design to be applied to the bar by a change in color of the surface portion of the bar exposed to the radiation passing through a portion of the shield.

As herein used the term "indicia" shall mean one or more symbols, figures, letters, trademarks, designs, patterns and the like identifying characters. The terms "two-colored" and "differently colored," as used to describe the color difference between the indicia portion and the remaining or background portion of the indicia soap bar, shall mean and refer to different colors or different shades of color for the indicia with respect to the color of the soap bar.

The term "soap" refers to the water-soluble ammonium, metallic, organic base salts of various fatty acids, such as soya, coconut oil and tallow which are chiefly lauric, myristic, oleic, palmitic and stearic acids. As used in this specification and claims, the terms "soap" and "soap bar" are intended to cover products in which soap is a substantial constituent, for example, bar, cake, flake and granular soaps; toothpaste; cleansing creams, and the like.

High energy electrons—that is electrons "shot" in a beam from an accelerator—have approximately a million times the energy of a typical chemical bond and about one hundred thousand times the energy required to ionize molecules. The energy of the beam of such electrons is measured in million electron-volts (mev.), where one mev. is defined as the energy carried by an electron accelerated across a voltage difference of one million volts. High energy electrons can cause electrical changes in substances such as dyes by ionizing and exciting molecules resulting in chemical-physical changes in the substance, such as a color change of the dye. The intensity of color change at any given depth of penetration for a given dye and soap system will be generally dependent upon the radiation dosage; and the depth of penetration of the color change into the soap bar will be generally dependent upon the electron beam energy.

Radiation dosage, measured in megarads (mrad) or millions of rads, is a function of the number of electrons impinging upon the substance being irradiated and the amount of energy lost per unit length of electron travel through the substance. One rad is 6.24×10^7 million electron volts per gram. The electron beam energy, measured in millions of electron volts (mev.), is a function of the accelerating potential through which the electrons pass before emerging from an accelerator as a high energy electron beam.

Referring to the drawings, our novel electron radiation-imprinted indicia soap bar is shown in perspective view in FIG. 2. The bar has an indicia 21 color-distinctive with respect to the remaining portion 23 of the bar. Such indicia 21 may be of any desired configuration and may be of either a different color or a different shade of color from the remaining portion 23. FIG. 3 is a cross section of the same soap bar illustrating the depth of the penetration of indicia 21 into the bar. Penetration of indicia 21 through about one-half of the soap bar, as defined by the solid line 22, will generally occur with single-side 3-6 mev. and 2-5 mrad irradiation of a bar of soap about 1 1/4 inches thick. Using thinner bars of soap or increased electron beam energy and dosage will cause the indicia to be imprinted throughout the depth of the bar, as illustrated by dotted lines 24 of FIG. 3. Full penetration of the indicia may also be achieved by irradiating the bar from both sides—that is, by double-bombardment of the bar. The same electron beam energy and dosage that will cause indicia 21 to penetrate about half-way through the bar on single-side irradiation, as illustrated in FIG. 3, will effect on double bombardment (from each side) an indicia 21 penetrating through the entire bar.

Either single bars or a plurality of bars, such as a tray of bars, may be irradiated. Rapid irradiation of the

bars may be by either a continuous operation or a batch operation. FIG. 1 schematically illustrates a tray-by-tray batch operation wherein a number of soap bars 11 are placed into tray 12, and shield 10 is then placed over the bars 11. By means of conveyor 13, the trays 12 are passed under a high energy electron beam source 9 so as to expose portions of the bars 11 to a predetermined electron beam energy and dose to result in indicia bars 22.

Shield 10 of FIG. 1, made of lead, brass, steel or other material impenetrable by the radiation, may be either of two types depending on whether only the indicia 21 portion of the indicia soap bar is to be irradiated or whether the background area 23 is to be irradiated.

To irradiate the background area 23 while shielding indicia area 21 of the soap bar, a male shield, FIG. 5, is used. This shield is formed of any radiation penetrable material 51, such as a sheet of rubber latex, onto which is fastened a number of radiation impenetrable designs 53, as shown in FIG. 5A. These designs are formed from lead or any other radiation impenetrable material.

Another type of shield is shown in FIG. 4. This is a female shield and consists of a sheet of lead 41 or any other radiation impenetrable material. A series of designs 43 are cut through or into sheet 41 so as to allow the radiation to pass through design 43, as illustrated in FIG. 4A. As shown in FIG. 6, design 43 of sheet 41 may be cut through sheet 43 so that walls 61 are substantially parallel to each other and perpendicular to upper surface 62 and lower surface 64 of design 43.

As shown in FIG. 6, when the penetrating radiation comes from an electron beam source in a spread beam, such as occurs when an indirect electron accelerator is utilized or when a number of bars are to be irradiated simultaneously, a certain amount of radiation passing through the design 43 will penetrate through the walls 61 and the lower surface 64 of the shield. Such radiation, although partially blocked by the radiation impenetrable material of the shield, may be sufficient to cause a lessened or partial color change of the soap bar color at area 64 of FIG. 6. Thereby the full radiation color change effect produced at area 62 of FIG. 6 may be surrounded by a partial color change of a different shade or color at area 64. This partial color change effect can be decreased or eliminated by tapering the aperture of the design through sheet 41 to conform the aperture to the path of the electron beam, as illustrated in FIG. 7. For example, using an electron beam scanning an angle of 16°, sharply defined indicia may be obtained by causing walls 65 to angle 16° into sheet 41 as illustrated in FIG. 7. Thus the full electron beam passes through the design and penetrates into the soap bar.

We have also found that incorporating certain dyes into the soap bar prior to irradiation greatly increases the color contrast, clarity and depth of penetration of the resulting indicia, and permits the use of lower electron beam energies and doses. Certain of these dyes when incorporated into soap cause a permanent color change of the irradiated area of the soap. Other dyes cause a color change of the irradiated area; but, upon aging of the bar, there is a gradual reversal of the radiation-induced color back toward its original non-irradiated color.

Azo dyes having a symmetrical arrangement of aromatic ring structures about the azo radical ($-\text{N}=\text{N}-$), as illustrated in FIGS. 8 and 9, exhibit a relatively irreversible color change upon incorporation into soap and irradiation. This irreversible effect will hereinafter be referred to as a "stable" color change. As an example of an azo dye exhibiting stable color change, External D&C Red No. 8 (Colour Index designation Acid Red 88) incorporated into soap at a level of 0.01% by weight results in a rose colored soap bar which undergoes, upon sufficient irradiation, a stable change to a gold color. The structural configuration of External D&C Red No. 8 is set out in FIG. 8, showing its symmetrical ring arrangement. Another example of an azo dye having a symmetrical ring arrangement is D&C Black No. 1 (Colour

Index designation Acid Black 1), shown in FIG. 9. This dye when incorporated into soap at a level of 0.01% results in dark blue colored soap which undergoes a stable color change to white upon sufficient irradiation.

Another azo dye, FD&C Yellow No. 6, structurally illustrated in FIG. 10, does not have a symmetrical ring arrangement around the azo radical. This dye does not exhibit the above-described stable color change when incorporated into soap and exposed to high energy electron irradiation; but exhibits a color change which gradually reverts back to its non-irradiated color. This reversibility can be minimized or arrested so as to achieve a stable radiation color change, by using a mixture of symmetrical and unsymmetrical azo dyes wherein at least 30% of the dye mixture is a symmetrical azo dye. For example, a dye mixture of 30% External D&C Red No. 8 and 70% FD&C Yellow No. 6 incorporated into soap at a concentration of 0.01% produces a stable color change upon radiation from red to yellow.

Still another dye, Genacryl Orange R (Colour Index designation Basic Orange R), exhibits stable color change in a soap gel.

This dye is not an azo dye as can be seen from its structure set forth in FIG. 11. When incorporated into a soap gel at a concentration of 0.11% by weight, Genacryl Orange R exhibits a rose color, which changes to a stable white color upon receiving a 6 mrad dosage at 11 mev.

Dyes exhibiting a gradually reversible change in color when incorporated into soap and irradiated, in addition to FD&C Yellow No. 6, include: FD&C Blue No. 1; FD&C Blue No. 1 Lake; D&C Blue No. 1; D&C Red No. 5; D&C Red No. 19; D&C Red No. 31; D&C Green No. 5; D&C Yellow No. 1; D&C Orange No. 5; methylene blue; quinone; azobenzene; and 2,3,5-triphenyl-2,4-tetrazolium chloride.

The suitable dyes, both the color stable and the color reversible and combination thereof may be added to the soap at any suitable step in the manufacture of the soap. We prefer to add the dye to the soap immediately prior to the plodding stage.

Relatively small amounts of the dyes are sufficient to obtain the advantages of this invention. Satisfactory results are obtained when the dye is present in a concentration of from 0.007% to 0.15% by weight on the basis of the weight of the soap. A preferred range is generally a weight concentration of about 0.01% to about 0.1%, although this will vary depending on the specific dye used and the colors desired. Practical considerations such as intensity of the color of the non-irradiated soap and cost factors limit the desirability of amounts much greater than 0.15%, although greater amounts can be used for greater contrast when desired. Amounts less than 0.007% will produce some color change in certain instances, but generally the color contrast between the irradiated and the non-irradiated portions of the soap will be less than is usually desired due to the lightness of the resulting soap colors. Absorbing the dye on titanium dioxide before incorporating it into the soap improves the intensity of the color change and the clarity of the indicia detail.

The intensity of radiation color change developed in any suitable dye-soap system is dependent on the radiation dose, measured in megarads, and the penetration of the radiation into the soap bar depends on the electron beam's energy, measured in mev. As a beam of electrons passes through a substance, the electrons are gradually slowed down. As the electrons slow down, they spend more time near each atom in the substance and thereby become more efficient at ionization. However the penetrating ability of an electron beam is proportional to its energy and inversely proportional to the density of the product being irradiated. Thus the beam energy theoretically required to penetrate an indicia half-way through a $\frac{3}{4}$ -inch thick bar of soap having a density of 1.020 grams/cc. is 2.1 mev. (as found by the Feather equation for calculating penetration of cathode ray beams).

FIG. 12 illustrates dosage variation for this bar of soap. As shown in FIG. 12, the dose that will be delivered to the bar of soap is not uniform to this calculated depth because the radiation dosage delivered to the bar of soap will vary with the depth of penetration into the bar for any given beam energy level. The cross-hatched area labeled "Side No. 1" of FIG. 12 shows the variation of penetration obtainable with single-side irradiation. The area labeled "Side No. 2" is a mirror image of the single-side radiation penetrating from the other side, as will be obtained with double-bombardment. A preferred minimum energy to achieve optimum dose half-way through this bar of soap is about 2.5 mev. This energy level may be used to imprint an indicia throughout the entire depth of this bar by irradiating the bar from both sides (double-bombardment combining the areas shown for Side 1 and Side 2).

Since dose and beam energy are independent variables, a particular color intensity and depth of penetration effect 20 can be produced by a number of beam energy-dosage combinations. FIG. 13 illustrates graphically the depth of penetration curves for some of the high energy electron beam levels that are useful in our process. Also, at any particular depth of penetration (measured in centimeters 25 in FIG. 13) the relative percent of ionization will be greater with a higher beam energy than with a lower beam energy. Increasing the dosage for a particular beam energy level acts to overcome that beam energy's lower percent ionization at particular depth and will produce a 30 color change effect equivalent to a lower dosage of a higher beam energy.

For soap bars containing a dye other than the particularly desirable color stable or gradually reversible dyes of this invention, higher energy and dosage equivalents 35 are preferable. For example, it appears that about 9 mev. and a dose from about 4.0 to 7.0 mrad, or the equivalent thereof, is suitable for a $\frac{3}{4}$ -inch soap bar to produce a gradually reversible indicia. For a $\frac{3}{4}$ -inch thick bar containing a suitable color reversible dye of this invention, 40 about 6 mev. at a dosage of 2 mrad is suitable. We have obtained desirable results for a $\frac{3}{4}$ -inch thick soap bar containing 0.0125% of the stable radiation-bleaching dye External D&C Red No. 8 when irradiated at 3.0 mev. and 4.0 mrad; an equivalent effect was achieved at 3.2 mev. at 3.0 mrad (due to the depth-dose curve relationship illustrated in FIG. 3). Adsorbing this latter dye on 45 titanium dioxide before incorporating the dye into the soap, and irradiating the bar by double-bombardment using the tapered female shield of FIG. 7 at 11 mev. and 6 mrad, resulted in an especially desirable indicia bar having a sharply defined distinctive white indicia imprinted with very little "fuzzing" of detail throughout the entire depth of the deep rose background bar.

In order to more fully describe this invention, the following specific examples are provided but without in any way limiting the invention thereto. In the specific examples hereinafter, the "soap bars" utilized contained about 15%-25% by weight sodium coco soap and 85%-75% by weight sodium tallow soap. Reference in the following examples to a "germicidal" soap means that a 50-50 mixture of 3,4,5-trichlorocarbanilide and hexachlorophene was added at a concentration of 1.5% by weight to the soap.

Example I

65 Bars of a germicidal soap, containing 0.00853% External D&C Yellow No. 1 and 0.00078% FD&C Yellow No. 6 dyes to give the bars a gold color, were tested for color change and for effect upon antibacterial properties 70 of the soap when irradiated with high energy electrons.

The bars were exposed to a 7 mrad dose at an electron beam energy of 3 mev. using a Van de Graff accelerator. The entire bar was exposed, resulting in an irreversible color change from gold to tan-brown. At lower doses, 75 such color change did not occur in these bars.

The irradiation did not appear to affect the antibacterial properties of the soap tested in vitro. The results of the tests on antibacterial properties showing minimum inhibition are set forth in Table I.

TABLE I

thickness of 0.03 inch. The image on the surface of the irradiated bar was good, but the fine detail of the design configuration was lost within about $\frac{1}{8}$ inch penetration into the bar. Even when the 0.03 inch brass base was milled out of the design, there was negligible improvement.

Double layers of $\frac{1}{16}$ inch thick lead sheets, through which the letter K approximately 1 inch high with arms $\frac{1}{16}$ inch thick was cut, were also used as shields. The K, was barely legible at a depth of about $\frac{1}{2}$ inch into the soap.

Example II

Using an Applied Radiation Corp. (ARCO) linear accelerator, operated at an electron beam energy of approximately 11 mev., samples of aqua, pink and gold colored germicidal soap bars weighing 4.99-5.11 oz. each and measuring $3\frac{1}{2} \times 2\frac{3}{16} \times 1.13$ inches were irradiated. The bars contained 0.0009% FD&C Blue Lake No. 1 and 0.0002% FD&C Yellow to give them an aqua color; 0.0073% FD&C Yellow No. 6 and 0.0002% Red No. 19 to give them a pink color; and 0.00853% External D&C Yellow No. 1 and 0.00078% FD&C Yellow No. 6 to give them a gold color.

In this example, the design to be imposed by radiation color change of the soap was cut through either a brass or lead shield so that the electrons passed through the design cut-out. The irradiated aqua soap bars were sectioned to determine the depth of color change and appearance of the indicia at each depth.

Table II shows the radiation dosages used, along with the observation of the appearance of the indicia. In all

Example III

Using the same equipment, soap bars and operating conditions as set out in Example II, aqua, pink and gold colored germicidal soap bars were irradiated at approximately 11 mev. using a male type of shield.

In this test the designs were cut from a $\frac{1}{16}$ inch thick lead sheet and secured to a rubber latex sheet so that the electrons could not pass through the design, thus silhouetting the design against a color-bleached background. The designs used in this test were the letters GK and HL, each letter approximately 1 inch high with arms $\frac{1}{8}$ inch wide, and the letter K approximately 1 inch high with arms $\frac{1}{16}$ inch wide.

The irradiated aqua bars were sectioned as set forth in Example II and the results, as indicated in Table III were superior to those obtained in Example II in that the non-irradiated-color design maintained reasonable contrast and clarity to nearly one-half the depth of the soap bars. Also a much lower dose produced sufficient color change to give satisfactory contrast.

cases it was necessary to deliver a radiation dose of at least 2 mrad, using an electron beam energy of 11 mev., to get satisfactory color contrast of the indicia into these bars. The aqua colored bars gave the best color contrast, although the color faded rapidly. The gold colored bars had fairly good contrast at the higher radiation dosages; and the pink colored bars gave only a faint color contrast.

When the brass shield was used, a $\frac{3}{8}$ inch by 1 inch crown design was first milled thereinto to a final brass

Example IV

A number of soap-dye systems were tested for color change, distinction of color contrast and color stability using $3.44-3.56$ oz., $3\frac{9}{16} \times 2\frac{3}{16} \times 1.20$ inch bars of soap without germicide and $3.58-3.70$ oz., $3\frac{1}{2} \times 2\frac{3}{16} \times 1.00$ inch bars of soap with germicide exposed to an electron beam energy of 8 mev. at a dose of 2 mrad from a linear accelerator.

In these tests, the soap bars containing dyes, were placed in $12\frac{1}{8} \times 12\frac{1}{8}$ inch aluminum trays $\frac{1}{8}$ inch thick

and having sidewalls 1½ inches high. Either a lead or steel shield was placed over the tray and the tray was passed under the beam of a linear accelerator to expose a portion of each bar to an electron beam energy of 8 mev. at a dose of either 0.6 mrad, 2 mrad or 3 mrad. The shields used were of the female type consisting of a 12 inch by 18 inch sheet of either ½ inch thick lead or ½ inch steel through which 1 x ¼ inch crown-shaped designs and 1 inch diameter circles had been cut through without tapering, such as is shown in FIG. 6.

The results of these tests are set forth in Tables IV-A, IV-B and IV-C. Table IV-A reports on germicidal soap bars whereas the bars listed in Table IV-B did not contain added germicides. Table IV-C reports on the effects of varying the dosage.

of the color distinction between the indicia and the soap background. The faded circle observed immediately after irradiation in certain test bars can primarily be attributed to the effect of the electron beam penetrating through part of the "fringe" area of the shield around the un-tapered design cut-out.

The effects of increasing the dose to 3 mrad and decreasing the dose to 0.6 mrad are not indicated in the tables; but it was observed that for this size bar of soap, the 3.0 mrad dose level resulted in a sharper color contrast than occurred with the 0.6 mrad level. At the lower dose level the circle indicia expanded from ½ inch on one face of the bars to about 1½ inches on the outer face of the bar. At the higher dose level, the circle indicia expanded from ½ inch to about 1¾ inches on the other

D&C Yellow No. 6	0.010	Yellow, tan indicia	Sl. fading	Faded
Quinone	0.010	White, light brown	Faded	
50% FD&C Blue No. 1 Lake and 50% D&C Red No. 19	0.0125	Violet, whiter indicia	Sl. fading	Fading
25% FD&C Blue No. 1 Lake and 75% FD&C Red No. 19	0.0125	Violet, faint pink indicia	do	Do.
50% Methylene Blue and 50% FD&C Yellow No. 6	0.0125	Dark blue background, gray indicia	Light blue	Do.
50% Methylene Blue and 50% D&C Red No. 19	0.0125	Blue, white indicia surrounded by 1/16 in. pink circle	do	Do.
98% FD&C Blue No. 1 Lake and 2% FD&C Yellow No. 6	0.0130	Blue, white indicia	Faint white	Faded
50% FD&C Blue No. 1 and 50% D&C Red No. 29	0.0125	Scarlet, white indicia	Faint	Fading
50% D&C Blue No. 1 and 50% D&C Red No. 19	0.0125	Deep violet, white indicia	Pink	Do.
22.5% D&C Red No. 19 and 77.5% FD&C Yellow No. 6	0.0125	Mild pink white indicia	Faint pink	Faded
22.5% FD&C Red No. 2 Lake and 77.5% FD&C Yellow No. 6	0.0125	Yellow-orange, white indicia	Fading	Do.
FD&C Red No. 2 Lake FD&C Yellow No. 6 and D&C Red No. 19	0.0075, 0.0030 and 0.0032	Pink background, white indicia	do	Do.
2,3,5-triphenyl-2,4-tetrazolium chloride	0.0125	Light yellow, very white indicia surrounded by 1/8 in. pink ring	Cream, pink ring still visible	Color mostly pink and only faintly visible

TABLE IV-C

[Effects of varying dosage at 11 mev. for 1 inch thick germicidal soap containing 0.0125% (basis: wt. of soap) of External D&C Red No. 8]

Design	Dosage, meg.	Size of indicia on—		
		Upper soap face, inch	Lower soap face, inch	Color contrast/ indicia/ background
Circle (½ inch)	0.6	½	1½	
	2.0	½	1½	
	3.0	½	1½	

The dyes reported in Tables IV-A and IV-B generally evidenced a gradual color reversibility—that is, within a month the radiation induced color reverted back toward the non-irradiated color, thereby resulting in a loss

side of the bar. Also the rate of fading was less at the higher dose than at the lower dose.

Example V

External D&C Red No. 8 dye was added to nongermicidal containing soap pellets and the soap bars formed therefrom were exposed to an electron beam energy of 8 mev. at a dosage of 2 mrad from a linear accelerator using the procedure set forth in Example IV. The results are set forth in Table V.

The results show External D&C Red No. 8 underwent stable color change from a rose to a gold color at this exposure, even when the concentration of this dye was cut in half by the addition of the generally reversible dye FD&C Yellow No. 6. In addition, the color change ap-

peared stable under 72 hours constant exposure to white fluorescent light and daylight.

an azo dye having a symmetrical arrangement of aromatic ring structure about the azo radical.

TABLE V

Dye	Percent dye in soap	Color and stability of indicia		
		1 hour	1 week	1 month
External D&C Red No. 8	0.0125	Rose background, gold indicia	Stable	Stable no fading
50% External D&C Red No. 8 and 50% FD&C Yellow No. 6	0.01604	Pink, yellow indicia	do	Do
50% External D&C Red No. 8 and 50% D&C Orange No. 4	0.0125	Orange-red, gold indicia	do	Do

Example VI

A series of 3.58-3.70 oz., 3 x 2 1/8 x 1 inch soap bars containing germicide and various dyes were irradiated and tested for color change and color stability.

The procedure used was that set forth in Example IV, except that the bars were exposed to an electron beam energy of 11 mev. The exposed bars received a radiation dosage of 2.0 and 6.0 mrad. The entire bar was exposed to electron radiation without shielding, so no indicia resulted.

The results are set forth in Table VI. The section of Table IV headed A contains results at the lower radiation dosage and the Section B contains results at the higher dosage.

It was observed that adsorption of the External D&C Red No. 8 dye upon TiO_2 caused a more intense color change upon irradiation without affecting color stability.

The effect of using D&C Black No. 1 as the test dye and exposing the bar to 11 mev. at 6.0 mrad was to produce a radiation color changed indicia which did not fade or tend to revert in color after one months' storage. This stable color change was not affected by exposing the irradiated bar to 72 hours of white fluorescent light and daylight.

4. The method of claim 1 in which said soap contains a mixture of azo dyes wherein at least about 30% by weight of said mixture is an azo dye having a symmetrical arrangement of aromatic ring structures about the azo radical.

5. The method of claim 1 in which said soap contains a dye selected from the group consisting of External D&C Red No. 8, D&C Black No. 1, and Genacryl Orange R.

6. The method of producing a multiple-color bar of soap which comprises directing high energy electron radiation toward a bar of soap containing at least 0.007% by weight of an electron radiation-sensitive dye, interpositioning between said bar and the source of the radiation a means for directing the radiation to a predetermined portion of the bar thereby causing a change in color of said predetermined portion of said bar.

7. The method of claim 6 in which said radiation-sensitive dye is present in an amount of at least 0.05% by weight of said bar.

8. The method of claim 6 in which said dye is an azo dye having a symmetrical arrangement of aromatic ring structure about the azo radical.

TABLE VI.—GERMICIDAL SOAP—DYE SYSTEMS INDICATING REVERSIBLE AND IRREVERSIBLE COLOR CHANGES WITHOUT INDICIA PRINTING

Dye	Percent dye in soap	Color and stability		
		1 hour	1 week	1 month
(A) At 2.0 megarad dosage:				
2,3,5-triphenyltetrazolium chloride	0.0125	Pink	Fading	Faded
D&C Black No. 1	0.0125	Violet	Violet	Violet, stable
D&C Red No. 5	0.0125	Faint yellow	Fading	Faded
D&C Red No. 31	0.0125	Cream	Cream	Sl. fading
External D&C Red No. 8 adsorbed on TiO_2	0.0125	Changed from rose to yellow	(1)	(1)
(B) At 6.0 megarad dosage:				
D&C Black No. 1	0.0125	White	White	White, stable
D&C Red No. 31	0.0125	Yellow	Yellow	Fading
External D&C Red No. 8 adsorbed on TiO_2	0.0125	Tan	Tan	Tan, stable
Triphenylphosphino silver nitrate	0.0125	Faint yellow	(2)	(2)
External D&C Yellow No. 1	0.0125	Faint cream	Sl. fading	Fading

¹ Same stability as without TiO_2 but has deeper color.

² Bar discoloring.

While the present invention has been described in an exemplified with respect to certain embodiments, it is not so limited; and it is to be understood that variations and modifications thereof, obvious to those skilled in the art, may be made without parting from the spirit and scope of our invention.

We claim:

1. A method of inducing a color change in a bar of soap selected from the group consisting of the water-soluble ammonium, metallic, and organic base salts of various fatty acids by irradiating at least a portion of said bar with high energy electrons.

2. The method of claim 1 in which said soap contains a dye.

3. The method of claim 1 in which said soap contains

9. The method of claim 6 in which said dye is a mixture of azo dyes containing at least about 30% of an azo dye having a symmetrical arrangement of aromatic ring structure about the azo radical.

10. The method of claim 6 in which said dye is an azo dye selected from the group consisting of External D&C Red No. 8, D&C Black No. 1, and Genacryl Orange R.

11. The method of claim 6 in which said means comprises a sheet of electron radiation penetrable material having affixed thereto an indicia, said indicia being impenetrable by high energy radiation so as to cause the configuration of the indicia to be applied to the bar of soap by exposure of a portion of the bar to the radiation through said shield.

12. The method of claim 6 in which said means comprises a sheet of electron radiation impenetrable material having an indicia aperture cut thereinto, said indicia being penetrable by at least a portion of said high energy electron radiation so as to cause the configuration of the indicia to be applied to the bar of soap by exposure of a portion of the bar to the radiation through said indicia.

13. The method of claim 12 in which said indicia aperture is tapered through the shield to substantially conform the aperture to the path of the high energy electron radiation.
